UNITED STATES PATENT OFFICE

133,137

DESIGN FOR A FLAG OR SIMILAR ARTICLE

Ira F. Wildey, Norfolk, Va.

Application March 12, 1942, Serial No. 106,177

Term of patent 3½ years

To all whom it may concern:

Be it known that I, Ira F. Wildey, a citizen of the United States of America, residing at Norfolk, county of Norfolk, and State of Virginia, have invented a new, original, and ornamental Design for a Flag or Similar Article, of which the following is a specification, reference being had to the accompanying drawing, wherein the figure is a plan view of a flag, showing my new design.

I claim:

The ornamental design for a flag or similar article, as shown.

IRIA F. WILDEY.
